UNITED STATES PATENT OFFICE.

HENRY F. SCHMIDT, OF PITTSBURGH, PENNSYLVANIA, ASSIGNOR TO WESTINGHOUSE ELECTRIC & MANUFACTURING COMPANY, A CORPORATION OF PENNSYLVANIA.

VENTILATING APPARATUS.

1,345,638.

Specification of Letters Patent.

Patented July 6, 1920.

Application filed July 13, 1914. Serial No. 850,804.

To all whom it may concern:

Be it known that I, HENRY F. SCHMIDT, a citizen of the United States, and a resident of Pittsburgh, in the county of Allegheny and State of Pennsylvania, have invented a new and useful Improvement in Ventilating Apparatus, of which the following is a specification.

My invention relates to ventilating and cooling apparatus, and it has special reference to ventilating devices adapted for use in connection with dynamo-electric machines, such as high-speed turbo-generators and the like.

The object of my invention is to provide ventilating apparatus whereby a large volume of air or other ventilating or cooling fluid is positively forced into the space to be ventilated or cooled by means of an impelling fan or blower of relatively small dimensions.

The single figure of the accompanying drawing is a longitudinal sectional view of a portion of a turbo-generator equipped with a ventilating device embodying my invention.

Large dynamo-electric machines, such as turbo-generators, especially such machines as are provided with closed end casings, generate more heat than can be dissipated by the currents normally set up by the rotating mechanism, and fans or blowers are therefore commonly employed for the purpose of forcing additional air through such machines.

However, the high peripheral speed at which many of these machines are driven renders it impossible to make the ordinary centrifugal blowers large enough to supply the necessary volume of air, although high air pressure is readily obtained. I have taken advantage of this latter fact, and succeeded in supplying a large amount of air with the use of relatively small fans, by conducting the air discharged by the fan through a narrow passage or whirl-chamber, of rapidly decreasing transverse section, into which opens a by-pass channel. The blast from the fan draws additional air through this by-pass channel, on the well-known principle of the steam injector.

The apparatus illustrated as embodying my invention may be equally well described

as consisting of a rotatable impeller, a whirl chamber surrounding the impeller and receiving the fluid discharged therefrom, a second whirl chamber surrounding the first chamber and receiving fluid discharged from the first chamber, and an inlet for the admission of fluid into the second whirl chamber. By so describing the apparatus, I consider the so-called by-pass channel in its broadest sense, that is, merely as an opening for the admission of fluid into the second whirl chamber; in addition to this I consider this inlet or opening as dividing the whirl chamber into two whirl chambers, the first surrounding the impeller and the second surrounding the first.

Considering the apparatus in this way the operation may be described as follows: The velocity energy of the fluid discharged from the impeller is partially converted into potential energy as the fluid traverses the first whirl chamber. Inasmuch as the outlet of the first whirl chamber communicates with a region of the same or approximately the same pressure as that of the main inlet to the propeller, the first whirl chamber will preferably be so designed as not to increase the pressure of the fluid materially above the pressure existing at the inlet or admission opening. The principal function of the first whirl chamber is therefore to prevent an abrupt building up of pressure immediately adjacent to the outlet of the propeller and a consequent loss of energy due to shock. The fact that the pressure of the fluid issuing from the propeller is gradually increased materially increases the efficiency of the impeller, since the gradual conversion of the velocity energy of the fluid leaving the impeller into pressure energy increases the flow of fluid through the impeller. The fluid issues from the first whirl chamber at a high velocity and in the form of an annular or disk shaped whirling jet. This jet in passing to the second chamber is exposed to, and consequently entrains fluid admitted through the inlet or admission opening between the two whirl chambers. The velocity energy of the disk shaped jet and the fluid entrained by it is converted into potential energy as represented by the increase in pressure as the fluid mixture passes through the second whirl chamber.

In the appa-

ratus illustrated the second whirl chamber delivers fluid to the cooling or ventilating passages of the apparatus to be cooled.

For a better understanding of my invention, reference may be had to the drawing, which shows portions of the rotor 1 and the stator 2 of a turbo-generator, the end turns 3 of the stator windings being inclosed, in the usual manner, in the cylindrical casing 4, one-half of which is shown in the drawing. The shaft 5 of the rotor 1 carries an annular support 6, upon which is mounted a centrifugal fan or impeller 7 that rotates with the shaft 5. An air chamber 8, communicating with the outer atmosphere, is connected by a channel 9 to the inlet of the impeller 7, and the air delivered by the impeller is received in an annular channel or whirl-chamber 10, of rapidly decreasing width, formed by annular partitions 11 and 12. These partitions 11 and 12 surround the shaft 5 in the relation shown, and are secured, in any suitable manner, to the walls of the casing 4. The whirl-chamber 10, at its narrowest part 13, communicates with a by-pass channel 14, by which connection is made between the channel 10 and the air chamber 8. From the point of union between the by-pass channel and the throat 13 of the whirl-chamber 10, the partitions 11 and 15 form a second whirl-chamber 16, which, as shown has parallel sides and which communicates with the casing 4 through the opening 17.

It will be observed that an acute angle is formed by the whirl chamber 10 and the channel 14, and that the air chamber 8 is sufficiently large to supply both the inlet 9 to the fan and the by-pass channel 14. It will also be readily understood that the air delivered by the blower 7 is compressed in the whirl-chamber 10 and passes the narrow throat 13 at relatively high velocity. The strong air blast thus produced tends to form a vacuum in the by-pass channel 14, and thus draws a considerable volume of air through this channel.

It will be observed that the kinetic energy of the whirling air blast generated by the centrifugal fan is utilized directly, in drawing additional air through the by-pass channel 14, without first being converted into pressure. The air delivered by the fan, and the air drawn through the by-pass channel 14, are mingled in the outer whirl-chamber 16, and all of the air is discharged into the casing 4 through the opening 17, its kinetic energy having, by this time, been almost wholly converted into pressure. From the casing 4, the air passes to the operating parts of the machine through suitable ventilating passages, which may be disposed in any convenient manner.

The resistance of the channel 9 to the passage of the air may be reduced, and the capacity of the fan-inlet increased, by pro-

viding the channel 9 with annular curved partitions 18, shown in section. These partitions are supported in spaced relation in the channel 9 in any convenient manner, for example, by the rods 19.

The structure shown and described may, if desired, be duplicated at the other end of the machine.

The device which I have described makes possible the use of relatively small fans for 75 cooling large machines, and also increases the cooling efficiency of the fan, because a large part of the air does not pass through the fan at all. Therefore, the increase in the 80 temperature of the air caused by friction within the fan is greatly reduced. My device has the additional advantage that larger 85 generators may be made self-cooling than is possible with the use of ordinary centrifugal fans.

Since many modifications may be made in my device without departing from the spirit and intent of my invention, I do not wish to be restricted to the precise structural details which I have shown and described, but it is 90 to be understood that no limitations are to be imposed unless indicated in the appended claims.

I claim as my invention:

1. A blower comprising a rotatably 95 mounted impeller and a stationary casing for said impeller, the said casing embodying air inlet and discharge chambers, a channel receiving fluid discharged from the impeller and communicating with the discharge chamber and a channel communicating with the first named channel and with the inlet chamber whereby air from said inlet chamber is caused to divide and pass partly through the blower and partly 105 through the last named channel.

2. A blower comprising a rotatably mounted impeller and a stationary casing for said impeller, the said casing embodying air inlet and discharge chambers, a channel 110 of varying cross section receiving fluid discharged from the impeller and communicating with the discharge chamber and a channel communicating with the first named channel and with the inlet chamber whereby 115 air from said inlet chamber is caused to divide and pass partly through the blower and partly through the last-named channel.

3. A blower comprising a rotatably mounted impeller and a stationary casing 120 for said impeller, the said casing embodying air inlet and discharge chambers, an annular channel of varying width receiving fluid discharged from the impeller and communicating with the discharge chamber and 125 a channel communicating with the inlet chamber and opening into the first named channel at an acute angle.

4. A blower comprising a rotatably mounted impeller and a stationary casing 130

for said impeller, the said casing embodying air inlet and discharge chambers, an annular channel of varying width receiving fluid discharged from the impeller and opening 5 into the discharge chamber and a channel communicating with the inlet chamber and opening into the first named channel at its narrowest point.

5. A blower comprising a rotatably mounted impeller and a stationary casing for said impeller, the said casing embodying air inlet and discharge chambers, an annular channel of varying width receiving fluid discharged from the impeller and 10 opening into the discharge chamber and a channel communicating with the inlet chamber and opening into the first named channel at its narrowest point and at an acute angle.
- 15 6. In combination in a fluid translating device, a rotatable impeller, a casing for the impeller, a whirl chamber surrounding the impeller and receiving the fluid discharged therefrom, a second whirl chamber surrounding the first whirl chamber and receiving the fluid issuing therefrom, and an inlet between the first and second whirl chambers and communicating with the inlet to the impeller for admitting additional 20 fluid to the second whirl chamber.
- 25 7. In combination in a fluid translating device, a rotatable impeller, a casing for the impeller, having an inlet port for deliver-

ing fluid to the impeller, a whirl chamber surrounding the impeller and receiving the 35 fluid discharged therefrom, and a passage for admitting an auxiliary supply of fluid into said whirl chamber at a point intermediate its inlet and outlet, said passage communicating with the inlet to the impeller 40 and being so formed as to direct the flow of fluid issuing therefrom in substantially the direction of the fluid traversing the whirl chamber.

8. In combination in a fluid translating 45 device, a rotatable impeller, a casing for the impeller, a stationary whirl chamber surrounding the impeller and receiving the fluid discharged therefrom, a second stationary whirl chamber surrounding the 50 first and receiving the fluid issuing therefrom, and an annular fluid admission port communicating with the inlet to the impeller and located between said whirl chambers for admitting additional fluid to said second chamber, and the walls of said admission port being so formed as to facilitate an entrainment of fluid by the stream of fluid issuing from the first whirl chamber.

In testimony whereof, I have hereunto 55 subscribed my name this 9th day of July, 1914.

HENRY F. SCHMIDT.
